CLAIM

The ornamental design for a fold and stack cart, as shown and described.

DESCRIPTION

FIG. 1 is a top perspective view of a fold and stack cart, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom view thereof;

FIG. 8 is a top perspective view of a fold and stack cart in a folded configuration thereof;

FIG. 9 is a front elevation view in a folded configuration thereof;

FIG. 10 is a rear elevation view in a folded configuration thereof;

FIG. 11 is a left side elevation view in a folded configuration thereof;

FIG. 12 is a right side elevation view in a folded configuration thereof;

FIG. 13 is a top plan view in a folded configuration thereof;

FIG. 14 is a bottom view in a folded configuration thereof; and,

FIG. 15 is a front elevation view in a folded configuration in an environment of use.

The broken lines in FIG. 15 depict environmental subject matter of additional folded carts and form no part of the claimed design.
